ABSTRACT OF THE DISCLOSURE

A plastic tank structure comprising a plurality of vertical tubular members. The tubular members can be hollow plastic tubes which are preferably placed around the circumference of a circle. Each tube is placed vertically adjacent another tube and a curable elastomeric sealant is imposed between the walls of adjacent tubes. The plastic tubes are attached together by joining means, such as bolts. The bottom end of each tube is firmly embedded in a base such as concrete. The enclosure formed by the perimeter of vertical plastic tubes is capable of storing liquids or solids. It is particularly useful for oil storage.

BACKGROUND OF THE INVENTION**(1) Field of the invention**

This invention relates to plastic tank structures. In particular, this invention relates to oil storage tanks having vertical plastic tubular wall segments.

(2) Description of the prior art

The problem of supplying large diameter storage tanks (i.e., 150 feet diameter) for storing oil or other liquids has been only partially solved by the prior art structures which are in the form of silos. The prior art structures are generally made of concrete or other ceramic elements. In some instances, hollow metallic building elements have been used which are then joined together and reinforced by filling them with concrete. Another approach has been to supply hollow ceramic building elements which interlock with adjoining elements to form a unitary structure. Several such structures are joined on vertically extending joint surfaces so that by utilizing a number of such units a vertically extending wall is formed. The problem with these prior art structures is that they are extremely expensive to fabricate, and are also very bulky and heavy. Furthermore, maintenance problems are severe in such structures because of corrosion, if metallic sections are utilized or because if one section of a ceramic unit is damaged it is extremely difficult to repair. It is virtually impossible to construct sections of prior art silos at locations removed from the building site, because of the nature of the building blocks used and the fact that they have to be cemented together.

SUMMARY OF THE INVENTION

In one of its broadest aspects the present invention encompasses a tank structure comprising a plurality of vertical tubular members having upper and lower ends. The tubular members are placed vertically adjacent one another and are joined by joining means. The tubular members are placed on the perimeter of any desired geometrical area thereby forming a wall around the perimeter and creating an enclosure within the walls which enclosure is adapted to store liquids or solids. The lower ends of the vertical tubular members are firmly embedded in a base material which forms the bottom of the structure.

2

The presently invented structure has several advantages over prior art structures. It is apparent that plastic tubular members or tubes of other material having a corrosion resistant coating or overwrap are resistant to abrasive forces and to corrosion from any liquids stored inside the tank. Furthermore, sections of a large tank, of say 150 feet diameter can be prefabricated away from the site of the tank because large wall sections can be constructed by bolting individual tubes together. Since these tubes are lightweight it is possible to carry sections of the structure to the site where they can all be joined together, preferably around the circumference of the circle to form a circular tank structure. Furthermore, such a tank is particularly resistant to seismic disturbances because of the resilience of the thin walled tubular members. If one section of such a tank becomes damaged, it is a relatively simple task to replace that section with another prefabricated section which has already been prepared and shipped to the site.

Accordingly, it is a primary object of the present invention to provide a container for the storage of solids or liquids having walls comprising thin walled tubular members set into a base.

It is another object of the present invention to provide a plastic tank structure which has a wall comprising plastic vertical tubular members set around the circumference of the circle and whose lower ends are set in a concrete base.

Yet another object of the present invention is to provide a tank structure which has a wall comprising metallic vertical tubular members having an overwrap of corrosion resistant reinforced plastic.

The novel features which are believed to be characteristic of the invention, both as to its organization and method of operation, together with further objects and advantages thereof will be better understood from the following description considered in connection with the accompanying drawing in which a presently preferred embodiment of the invention is illustrated by way of example.

It is to be expressly understood, however, that the drawing is for the purpose of illustration and description only, and is not intended as a definition of the limits of the invention.

BRIEF DESCRIPTION OF THE DRAWINGS

FIG. 1 is a front elevation of the invented tank structure. FIG. 2 is a plan view of several of the tubular members and their joining means.

FIG. 3 is a partially sectioned perspective of a tubular member and its joining means.

DESCRIPTION OF THE PREFERRED EMBODIMENTS

The invented plastic tank structure has been found particularly advantageous for the storage of oil and will accordingly be described in connection with such use.

With reference now to FIG. 1 a plastic tank structure 10 comprises vertical tubular members 12 which can be set on the circumference of a circle. It is of course within the scope of the invention to set the tubular members on the perimeter of any geometrical area thereby forming an enclosure of the desired configuration. It is, however, highly advantageous for the storage of oil to set the tubular members on the circumference of a circle. Typically, the diameter D of such a structure can be from about 60 feet to about 150 feet. The tubular members can conveniently be 20 feet long and 40 inches inside diameter,

and can be about 0.10 inch minimum thickness. In the preferred embodiment of the invention the tubular members are set into a concrete base which forms the floor of the plastic structure.

The tubular members 12 are preferably of plastic. They must be of a material that is impervious to the contents of the tank structure. In this case they must be impervious to hydrocarbon oil and must have sufficient mechanical strength to oppose the forces put upon them by full tanks of liquid or of seismic forces that may occur. In a 20 foot tank containing water the pressure at the base of the tank will be approximately 8 p.s.i. One preferred method of fabricating such tubular members is by the filament winding process wherein a glass cloth is impregnated with an elastomeric polyurethane or other thermosetting resin. Several layers of such glass cloth are overwrapped on a mandrel. The pipe thus formed is then cured and removed from the mandrel leaving the hollow tubular member. The polyurethane resin used comprises a polyhydroxide compound and an isocyanate prepolymer used in sufficient quantities to effect a cure of the resin and to make it tough and resilient, yet having sufficient rigidity to withstand the mechanical force requirements of the structure. Such filament wound tubes have the advantage of being lightweight and corrosion resistant and also have high tensile strength and can resist high bending moments. Alternatively the tubular member can comprise a tube of extruded plastic such as polyvinyl chloride which is then reinforced by an overwrap reinforcing layer of fibre glass impregnated with any particular resin which can then be cured; or if the extruded plastic that is used meets a mechanical strength requirement and has the chemical corrosion resistance required, no overwrap need be applied. Finally, thin gage steel or other metal tubes, straight walled or corrugated, may be used which can then be overwrapped with a reinforcing layer of resin impregnated fibre glass.

Between each tube and the adjacent tube is placed a layer of sealant 14. This sealant can be made of any resilient material that is nonreactive with the contents of the plastic tank structure. In this particular case the sealant material must be nonreactive with hydrocarbon oils. One such tough resilient material that may be used as a sealant is a polyurethane elastomer comprising a polyhydroxide compound and a polyisocyanate prepolymer material mixed in sufficient quantities to promote cure of the sealant material. This sealant serves the function of caulking the spaces between the tubular members to prevent any liquid inside the tank from leaking out. It also serves the function of forming a bond between adjacent tubes thereby holding them together, to resist shear forces due to seismic or other loads. In addition to the sealant which bonds the tubes together, the tubes are held together by a series of bolts 16, 16a and 16b.

Referring now to FIGS. 2 and 3 there is shown a means by which tubular members 12 are joined to one another. Inside the hollow tubular members and running vertically the whole length of them, there are bars of material 18 and 18a. These bars can conveniently be of wood or of any other material which has sufficient strength to resist warping when the bolts joining one tube to the next tube are tightened. The wooden bars 18 and 18a are placed at opposite sides of the inside of the tubular member and holes are drilled therethrough to allow bolts to be inserted through the wall of one tube and through the wall of an adjacent tube and through the wooden bar in the adjacent tube. Alternatively steel washers contoured to the curvature of the tube can be used in conjunction with fastening bolts. Such bolts can be spaced at various positions along the vertical axis of the wooden bars. The bolts can conveniently be positioned at three points equally spaced along the length of the tube thus bolts 16, 16a, 16b join one tubular member to the adjacent member. To meet loading requirement $\frac{3}{4}$ inch bolts can be used spaced at equal distance throughout the length of the tube. For

some applications this spacing will be about 6 inches and for other applications if high tensile bolts are used, the spacing can be greater. Between the two tubes is a layer 14 of sealant material as previously described. When the bolts are tightened, the wooden bars allow a large torque force to be applied to the bolts without warping and without damaging the walls of the tubes themselves. Thus the tubes are not only joined by the adhesive forces of sealant 14, but also by the bolts which can be tightened to any desired degree. The whole structure is resistant to seismic or other mechanical forces which would tend to force apart the tubular members. In addition reinforcing plates can be attached to the base of the tank and to the concrete base to resist forces that would tend to overturn the tank. If it is desired to stabilize these tubular members against buckling or other mechanical forces it is possible to fill them with the same fluid that is in the tank. This has the effect of counteracting the compressive forces on the wall of the tubing.

10 The tubular members can be set around the circumference of a circle and their lower ends embedded into a base material to a predetermined depth which will promote stability of the structure. The base material can conveniently be concrete which is impervious to oil and other liquids. The tubular members could also be set into the ground which can then have concrete or other material impervious to liquids placed over it.

15 It is apparent from the foregoing description that the plastic tank structure which is the subject of the present invention is advantageous in that it provides a corrosion resistant and lightweight structure for the storage of oil or other liquid or solid materials. Another advantage of the present invention is that it can be constructed in sections and easily transported to the proposed building site. Furthermore, if any particular segment of the wall of such a structure is damaged, the damaged tubular members can easily be disconnected and replaced by new members. Another advantage is that the high strength of these plastic tubes is such that they resist bending moments caused by seismic or other loading forces. Finally, the whole structure is relatively inexpensive to construct when compared to the prior art ceramic silos which require cementing and other large expenditures of labor.

20 I claim:

1. A wall for a tank structure comprising:
a plurality of elongated tubular members;
a plurality of bars, at least two of which are disposed on the inside of each of said plurality of tubular members and which extend along the length of said tubular members;
joining means, for rigidly coupling one of said bars in said tubular members with one of said bars in another of said tubular members thereby joining two of said tubular members between said bars, said joining means coupling all of said bars to form a continuous wall of said tubular members.

2. The structure defined in claim 1 wherein said joining means comprises bolt means disposed through said bars and said tubular members.

3. The structure defined in claim 2 wherein a sealant is disposed along the outside length of said tubular members adjacent to said plurality of bars, for sealing said tubular members to one another.

4. The structure defined in claim 3 wherein said sealant comprises an elongated member of resilient material.

5. The structure defined in claim 3 wherein said sealant is a curable elastomeric resin.

6. The structure defined in claim 5 wherein said sealant is a curable elastomeric polyurethane resin.

7. The structure defined in claim 1 wherein said tubular members are made of resin impregnated glass fibers.

8. The structure defined in claim 1 wherein said tubular members are made of extruded plastic having a resin impregnated glass tape overwrap.
